UNITED STATES PATENT OFFICE.

CECIL SHAW, OF HUDDERSFIELD, ENGLAND.

DYEING OF WOOL AND/OR SILK.

No Drawing. Application filed November 7, 1927, Serial No. 231,776, and in Great Britain November 26, 1926.

The invention relates to the dyeing of wool and/or silk, in the course of experiments in which we have found that certain water-soluble hydroxy-halogen-benzoquinones have 5 a strong affinity for such fibres, both when mordanted and unmordanted, and are capable of being fixed to give very fast shades.

The invention consists in the employment, 10 as dyestuffs for wool and/or silk, of 1.4 di hydroxy 2.5 dichlor benzoquinone or 1.4 di hydroxy 2.5 dibrom benzoquinone, such dyestuffs being applied from an ordinary acid 15 dye bath and fixed by afterchroming or by immersion in a boiling solution of a suitable metallic salt. The structural formulas for 20 the hydroxy-halogen-benzoquinones specified are as follows:

As an example, 1.4 di hydroxy 2.5 dichlor quinone dyes wool from an ordinary acid 35 dye bath giving red brown shades which, if afterchromed in the usual way, are very fast.

In place of afterchroming, the dyed fibre or fabric may be immersed in a boiling solution of a metallic salt, such as copper sulphate, ferrous sulphate or equivalent, it being found that a metallic salt which precipitates 40 an insoluble salt of the quinone usually gives the fastest shade.

1.4 di hydroxy 2.5 dibrom quinone may be 45 employed in the same manner as above described with similar or substantially similar results.

Having thus described my invention, what I claim as new and desire to secure by Letters Patent is:—

1. In the dyeing of wool and/or silk, the 50 employment as dyestuffs of water-soluble 1.4 di hydroxy 2.5 di halogen-benzoquinones applied from an acid dye bath.

2. The dyeing of wool and/or silk by means of 1.4 di hydroxy 2.5 dichlor benzoquinone applied from an acid dye bath.

55 In testimony whereof I affix my signature.

CECIL SHAW.
